BOILER

Howard J. Kerr, Westfield, N. J., assignor to The Babcock & Wilcox Company, Bayonne, N. J., a corporation of New Jersey

Application August 19, 1932, Serial No. 629,471

13 Claims. (Cl. 122—299)

The present invention relates in general to the construction and operation of steam boilers of the water tube type, and more particularly, to water tube boilers in which the generation of steam is effected in a bank of natural circulation tubes connected to a steam and water drum located at a substantial distance above the uppermost point of steam generation in the tube bank, whereby the circulation of the fluid in the tube bank is substantially increased by the high hydraulic head to which it is continuously subjected.

The general object of my invention is the provision of a water tube steam boiler of high thermal efficiency, great structural strength, and capable of construction at a relatively low cost. A further and more specific object is the provision of a water tube boiler with a compact and thermal efficient arrangement and a simplified construction of the auxiliary fluid heating surface advantageously incorporated therein. A further specific object is the provision of a steam boiler having a substantial amount of fluid heating surface distributed throughout a vertical gas pass with an improved construction for equalizing the heating gas flow through all portions of the gas pass.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation with parts broken away of a high drum water tube boiler constructed in accordance with my invention; and

Fig. 2 is a vertical section on an enlarged scale taken transversely to Fig. 1.

In the embodiment of my invention illustrated in the drawings, 10 indicates a furnace chamber formed by vertical front and rear walls 11 and 12 respectively, and side walls 13, the front and rear walls terminating at their lower ends in inclined ash receiving surfaces 14 discharging at their lower ends into an ash hopper 14a. The front wall of the furnace has an inwardly arched section 15, through which fuel burner nozzles 16 and air conduits 16a discharge comminuted fuel and air into the furnace chamber. The furnace walls are lined by radiant heat ab-

sorbing fluid conduit elements 17 connected at their upper and lower ends to horizontal headers 18 and 19 respectively. Horizontal intermediate headers 19b are interposed at the junction of the vertical and inclined portions of the front and rear walls. Each pair of headers 18 and 19 is independently connected to the boiler steam and water space by circulators 18a and 19a respectively, which for convenience of illustration are broken away. Recirculation in each water wall section is provided by external connectors 20. The vertical portion of the wall section 15, the side walls 13 and rear wall 12, cooperate to form a gas outlet from the furnace chamber registering with the lower end of a vertical gas pass 21, which as shown, has substantially the same cross-sectional area throughout its height.

In the lower end of the gas pass 21 is arranged a natural circulation bank of horizontally inclined steam generating tubes 22 having their opposite ends expanded into vertical downtake and uptake headers 23 and 24 respectively. The lower rows of the tubes 22 are more widely spaced than the upper rows of the bank to provide a slag screen for the upper rows and for any fluid heating surface located in the upper portions of the gas pass.

The downtake headers 23 are connected to the water space of a transversely extending steam and water drum 25 by a series of downtake circulators 26. The circulators 26 are bent adjacent the headers to form inner and outer rows 26a and 26b respectively, the tubes of the inner row 26a being covered with heat insulating material to form a wall 26c defining the rear side of the gas pass for a substantial distance above the headers 23 but short of the lower side of the drum 25. The headers 24 are connected by a row of uptake circulators 27 extending vertically therefrom along and lining the front wall of the gas pass 21 and having horizontal portions 27a lining the boiler roof and expanded into the drum 25. The drum 25 is protected from direct contact with the heating gases by a covering 31 of heat insulating material.

High drum boilers of the general type described have been heretofore provided with auxiliary fluid heating surface, such as a superheater or economizer, which for various reasons has been located either above the steam and water drum, with a consequent increase in height of the boiler, or in a second gas pass of the unit. In accordance with the present invention, auxiliary heating surface consisting of a superheater, econo-

mizer and steam re heater, is positioned in the portion of the gas pass 21 bounded by the tube bank 22, uptake and downtake circulators, and the steam and water drum 25. The superheater used advantageously consists of a plurality of rows of long return bend tubes 33, corresponding tubes in the adjacent rows being nested and the tubes in each row being arranged in parallel vertical planes and extending immediately above the tube bank 22. Opposite ends of the tubes 33 are connected to inlet and outlet headers 34 and 35 respectively, positioned externally of the tube wall 26^c. Advantageously, the steam flow in the superheater tubes is generally parallel to the flow of high temperature heating gases, acquiring the desired amount of superheat, while affording the lowest tube temperatures. The portions of alternate superheater tubes in each row passing through the circulator wall 26^c are bent to conform to the circulator spacing and to permit the radial connection of the tubes into the headers 34 and 35. The superheater inlet header 34 is connected to the steam space of the drum 25 by steam circulators 36 and the outlet header 35 to a steam main.

The steam re heater consists of a plurality of rows of tubes 37 constructed and arranged similarly to those of the superheater and having their end portions connected to inlet and outlet headers 38 and 39 respectively, the latter being arranged to provide a steam flow through the re heater generally counter to the heating gas flow and opposite to the steam flow in the superheater. The temperature of the heating gases at the point in the gas pass at which they contact with re heater tubes will be such that the normal tube metal temperature will not be sufficiently high as to cause the tubes to deteriorate, and the most effective heat transfer will be obtained by a counterflow of the steam therein. The re heater inlet header 38 may be connected, for example, to the exhaust end of one pressure stage of a turbine, and the outlet header 39 to the inlet end of the next stage of the turbine.

In prior construction of water tube boilers of the character described, the economizer surface has been usually located in a low temperature portion of the boiler and usually above the level of the steam and water drum. In the present construction the economizer surface is advantageously positioned in the portion of the vertical pass 21 bounded by the re heater, circulators, and steam and water drum. The economizer illustrated is divided into two superposed sections 40^a and 40^b, each consisting of a single row of long return bend tubes 40, making a number of turns back and forth across the gas pass and arranged in parallel vertical planes. The end portions of the tubes in the lowermost leg of the upper section and those in the uppermost leg of the lower section project through the circulator wall 26^c and are detachably connected by nested return bends 40^c. The water flow through the economizer surface, like the steam flow in the re heater, is generally counter to the direction of heating gas flow, the uppermost legs of the tubes in the section 40^a and the lowermost legs of the tubes in section 40^b being connected to the economizer inlet and outlet headers 41 and 42 respectively, at the outer side of the wall 26^c. The inlet header 41 is connected to the feed water supply system and the outlet header 42 is connected to the drum 25 by circulators 43.

The uppermost economizer tube legs are positioned at a level substantially below the level of

the drum 25, leaving a space 44 of substantial volume in the uppermost portion of the gas pass 21. A gas exit passage 45 extends horizontally from the rear side of the space 44, the lower side of the passage being formed by a lateral extension of the wall 26^c. The downtake circulators 26, economizer connectors 43, and superheater connectors 36 all extend through the gas exit passage to their points of connection with the drum 25. Heating gases leaving the passage 45 are divided between parallel vertical outlet flues 46, in each of which air heating surface is preferably arranged, receiving cold air from an inlet 47 and delivering the heated air to a common outlet 48. This arrangement of a gas outlet of relatively restricted flow area at the upper rear side of a baffleless vertical gas pass, tends to cause drifting of the heating gases rearwardly during their upward flow through the gas pass 21. This tendency is substantially eliminated in the present construction by the arrangement and volume of the space 44, which acts as a pressure equalizing space, and advantageously provides a uniform distribution of the heating gases throughout the cross-sectional area of the gas pass. If the gas exit 45 is arranged in the roof of the boiler and of large cross-sectional area, the size of the space 44 can be substantially reduced.

The relatively large amount of fluid heating surface included in the gas pass 21 presents an involved problem of supporting the same. In the present construction, all of the boiler unit above the furnace chamber is enclosed by a supporting steel work 49, and comprises horizontal beams 50 extending across the top of the boiler. Each auxiliary fluid heating section is supported by and between the uptake and downtake circulators 27 and 26^a respectively. As indicated in Fig. 1, the uppermost return bend portion of each economizer tube is provided with a lug 51 welded thereon and engaging a lug 52 carried on a corresponding portion of the uptake circulators 27. The next set of return bend portions at the downtake side of the gas pass are also provided with lugs 51 engaging lugs 53 on the corresponding downtake circulators 26^a. The lower rows of tube legs of each economizer section are spaced and supported by short narrow plate members 54, extending between and welded to adjacent superposed tube legs. The connections 54 of adjacent tube legs are alternately positioned at opposite sides of the gas pass, the plate connectors at each side being arranged in parallel diagonal rows which meet the rows of the opposite side at the center line of the economizer. The plates 54 unite with the tube metal to form a supporting truss for each economizer section. This independent supporting arrangement for the superposed economizer sections, coupled with the external detachable connections therebetween facilitates the installation and removal of the individual sections, simplifies the manufacture and provides an effective way of incorporating economizer surface of any desired area.

In the superheater and re heater illustrated, the nesting tube rows make three return bends. The superheater is supported by coacting lugs on the lowest return bend and uptake circulators, and at its opposite end by similar lugs on the middle return bend and downtake circulators. The re heater supports consist of coacting lugs on the uppermost return bend and uptake circulators and a similar support between the middle return bend and downtake circulators. Corresponding tubes in the parallel rows and adjacent legs of the

same tube in the superheater and reheater are interconnected by plate members 55 similar in form to the plate members 54 of the economizer sections, but arranged in one or more vertical rows at each end of the superheater and reheater.

The combined drum, heating surface and circulator structure so formed is supported from the steel work 49 by straps connecting the same to the beams 50. As shown in Fig. 1, straps or rods 56 are welded on to the vertical portion of the uptake circulators 27, the point of connection being designated 57. The upper ends of the straps 56 are adjustably connected to the beams 50. U-shaped straps 58 connect the drum 25 and the fluid heating surface supported therefrom to the beams 50, and straps 59 carry the circulators 36 positioned between the rear wall of the gas pass 21 and the flue 46. The supporting means described provide an effective and practicable arrangement for maintaining the various boiler parts in position, while permitting their expansion and contraction in operation.

In the operation of the water tube boiler illustrated, fuel is burned in the furnace chamber 10, and the heating gases generated, after passing through a generally U-shaped flow path in the furnace chamber, pass upwardly through the gas pass 21. The furnace chamber temperatures are maintained within the desired operating limits by the absorption of radiant heat by the water circulating in the furnace wall tubes. The heating gases pass successively over the natural circulation steam generating bank, superheater, reheater, and economizer units, being uniformly distributed throughout the area of the gas pass by the action of the flow equalizing space 44. The temperature of the gases is substantially lowered by their passage over the water tubes 22 and superheater tubes 33; a steam flow, however, through the superheater tubes parallel to the flow of the heating gases, being desirable to avoid excessive metal temperatures therein. The temperature of the gases leaving the superheater will be considerably higher than the saturated steam temperature and sufficient to effect a substantial superheating of the steam flowing through the re-heater. An effective heat transfer relation is maintained in this portion of the gas pass by the counter current flow of fluid through the economizer and re-heater tubes. These elements absorb a large portion of the heat remaining in the heating gases, and permit them to be safely passed across the various connectors located in the gas exit passage. Some of the heat remaining in the gases is utilized for heating the air for combustion before the gases pass to the stack.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. In a high drum water tube boiler, a furnace chamber, fuel burning means in said chamber, a vertical heating gas pass arranged above said furnace chamber, a bank of steam generating tubes positioned in said gas pass, a steam and water drum positioned at a level substantially above the uppermost portion of said tube bank, a row of

circulators at each end of said tube bank connecting said steam and water drum and tube bank to form a natural circulation steam generating section, an economizer positioned in said gas pass in the space bounded by said tube bank and circulators and below said steam and water drum and comprising a plurality of superposed tube sections, each formed by return bend tubes arranged in parallel, means providing a serial flow through said economizer sections, and means for independently supporting said economizer sections from one of said rows of circulators.

2. In a high drum water tube boiler, a furnace chamber, fuel burning means in said chamber, a vertical heating gas pass arranged above said furnace chamber, a bank of steam generating tubes positioned in said gas pass, a steam and water drum positioned at a level substantially above the uppermost portion of said tube bank, uptake and downtake circulators connecting said steam and water drum and tube bank to form a natural circulation steam generating section, an economizer positioned in said gas pass in the space bounded by said tube bank and circulators and below said steam and water drum and comprising a plurality of superposed tube sections, each formed by return bend tubes arranged in parallel, means providing a serial flow through said economizer sections, and means for independently supporting said economizer sections from one of said uptake and downtake circulators.

3. In a high drum water tube boiler, a furnace chamber, fuel burning means in said chamber, a vertical heating gas pass arranged above said furnace chamber, a bank of steam generating tubes positioned in said gas pass, a steam and water drum positioned at a level substantially above the uppermost portion of said tube bank, uptake and downtake circulators connecting said steam and water drum and tube bank to form a natural circulation steam generating section and defining a portion of said gas pass, an economizer positioned in said gas pass in the space bounded by said tube bank and circulators and below said steam and water drum and comprising a plurality of superposed tube sections, each formed by return bend tubes arranged in parallel, means detachably connecting said economizer sections externally of said gas pass and providing a serial flow therethrough, and means for independently supporting said economizer sections from said uptake and downtake circulators.

4. In a high drum single pass water tube boiler, a furnace chamber, fuel burner means in said chamber, a vertical heating gas pass arranged above said furnace chamber, a bank of steam generating tubes positioned in the lower portion of said gas pass, a steam and water drum positioned at a level substantially above the uppermost portion of said tube bank, uptake and downtake circulators connecting said drum and tube bank to form a natural circulation steam generating section, auxiliary fluid heating surface positioned in the portion of said gas pass bounded by said uptake and downtake circulators and tube bank and below said drum, a pressure equalizing space of substantial height and volume between said auxiliary fluid heating surface and said drum, and a heating gas outlet opening to one side of said space.

5. In a high drum single pass water tube boiler, a furnace chamber, fuel burner means in said chamber, a vertical heating gas pass arranged above said furnace chamber, a bank of horizontally inclined steam generating tubes positioned in

- the lower portion of said gas pass, a steam and water drum positioned at a level substantially above the uppermost portion of said tube bank, uptake and downtake circulators connecting said drum and tube bank to form a natural circulation steam generating section, auxiliary fluid heating surface positioned in the portion of said gas pass bounded by said uptake and downtake circulators and tube bank and below said drum and including an economizer positioned above said tube bank and below said drum and leaving a pressure equalizing space of substantial volume between said economizer and said drum, and a heating gas outlet from said pass opening to one side of said space.
6. In a high drum single pass water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, uptake and downtake circulators connecting said steam and water drum and tube bank to form a natural circulation steam generating section, auxiliary fluid heating surface positioned in the portion of said gas pass bounded by said uptake and downtake circulators and tube bank and below said steam and water drum and including a steam superheater positioned above said tube bank and having a steam flow therein parallel to the flow of heating gases, an economizer positioned above said superheater and below said drum and having a water flow therein counter to the flow of heating gases and leaving a pressure equalizing space of substantial volume between said economizer and said drum, and a heating gas outlet from said pass opening to one side of said space.
7. In a high drum single pass water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, uptake and downtake circulators connecting said steam and water drum and tube bank to form a natural circulation steam generating section, auxiliary fluid heating surface positioned in the portion of said gas pass bounded by said uptake and downtake circulators and tube bank and below said steam and water drum, and including a steam superheater positioned above said tube bank, a steam reheater positioned above said superheater, an economizer positioned above said reheater and below said drum and leaving a pressure equalizing space between said economizer and said drum, a heating gas outlet from said space, and means for independently supporting said superheater, reheater and economizer from said uptake and downtake circulators.
8. In a high drum single pass water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, steam and water circulators connecting said drum, uptake and downtake circulators connecting said steam and water drum and tube bank to form a natural circulation steam generating section, auxiliary fluid heating surface positioned in the portion of said gas pass bounded by said uptake and downtake circulators and tube bank and below said steam and water drum, and including a steam superheater and an economizer, to form a natural circulation steam generating section, auxiliary fluid heating surface positioned in the portion of said gas pass bounded by said uptake and downtake circulators and tube bank and below said steam and water drum, and including a steam superheater positioned above said tube bank and having a steam flow therein parallel to the flow of heating gases, a steam reheater positioned above said superheater and having a steam flow therein counter to the flow of heating gases, an economizer positioned above said reheater and below said drum and having a water flow therein counter to the flow of heating gases and leaving a pressure equalizing space of substantial volume between said economizer and said drum, a heating gas outlet from said pass opening to one side of said space, and means for independently supporting said superheater, reheater and economizer.
9. In a water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned above said tube bank, rows of uptake and downtake circulators connecting said steam and water drum and tube bank to form a natural circulation steam generating section, auxiliary fluid heating surface positioned between said rows of uptake and downtake circulators, above said tube bank, and below said steam and water drum, and including a steam superheater and an economizer, each comprising a bank of multi-looped return bend tubes, and means for independently supporting the looped portions at one end of said superheater and economizer tube banks from one of said rows of circulators.
10. In a high drum water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, rows of uptake and downtake circulators connecting said steam and water drum and tube bank to form a natural circulation steam generating section, auxiliary fluid heating surface positioned between said rows of uptake and downtake circulators, above said tube bank, and below said steam and water drum, and including a steam superheater and an economizer, each comprising a bank of multi-looped return bend tubes having their looped portions at each end contacted by heating gases, and means for independently supporting one end of said superheater and economizer tube banks from one of said rows of circulators.
11. In a high drum single pass water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, rows of uptake and downtake circulators connecting said steam and water drum and tube bank to form a natural circulation steam generating section, auxiliary fluid heating surface positioned in the portion of said gas pass bounded by said uptake and downtake circulators and tube bank and below said steam and water drum, and including a steam superheater and an economizer,

each comprising a bank of multi-looped return bend tubes having their looped portions at each end within said gas pass, and means for independently supporting the opposite ends of said superheater and economizer tube banks from said rows of uptake and downtake circulators.

12. In a high drum water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, rows of uptake and downtake circulators connecting said steam and water drum and tube bank to form a natural circulation steam generating section, auxiliary fluid heating surface positioned between said rows of uptake and downtake circulators above said tube bank and below said steam and water drum, and including a steam superheater, a steam re-heater, and an economizer, each comprising a bank of multi-looped return bend tubes having their looped portions at each end contacted by heating gases, and means for independently supporting one end of said superheater, re-heater and

economizer tube banks from one of said rows of circulators.

13. In a high drum single pass water tube boiler, a furnace chamber, fuel burner means in said chamber, a vertical heating gas pass arranged above said furnace chamber, a bank of horizontally inclined steam generating tubes positioned in the lower portion of said gas pass, a steam and water drum positioned at a level substantially above the uppermost portion of said tube bank, rows of uptake and downtake circulators connecting said steam and water drum and tube bank to form a natural circulation steam generating section, auxiliary fluid heating surface positioned in the portion of said gas pass bounded by said uptake and downtake circulators and tube bank and below said steam and water drum, and including a steam superheater positioned above said tube bank, a steam re-heater positioned above said superheater, an economizer positioned above said re-heater and below said drum, a heating gas outlet above said economizer, and means for independently supporting said superheater, re-heater and economizer from said rows of uptake and downtake circulators.

HOWARD J. KERR.
